SHOE

Irl B. Calvin, Akron, Ohio

Application February 7, 1935, Serial No. 5,353

10 Claims.

(Cl. 36—12)

The present invention relates to an improvement in shoes and has for its primary object to produce a shoe which is simple in construction, has practical utility, is of pleasing and attractive appearance, and is inexpensive to manufacture.

A further object of the invention is to produce a shoe of the knock-down or fabricated type which is easily assembled by the user, thus offering a personal incentive and materially reducing 10 the ultimate cost to the user.

A still further object of the invention resides in providing a sole for the shoe, preferably of molded rubber, and constructed in such a manner as to reduce to a minimum the possibility of 15 water leaking therethrough.

With the objects above indicated and other objects hereinafter explained in view, the invention consists in the construction and combination of elements hereinafter described and claimed.

20 Referring to the drawings:

Figure 1 is a side elevational view of a shoe embodying the present invention;

Figure 2 is a bottom plan view of the shoe illustrated in Figure 1;

25 Figure 3 is a fragmentary, longitudinal, sectional view of the toe portion of the shoe illustrated in Figure 1;

Figure 4 is a transverse, sectional view taken on line 4—4 in Figure 1 showing more clearly the 30 structural details;

Figure 5 is a side elevational view of a modified form of shoe sole embodying the present invention;

Figure 6 is a fragmentary, transverse, sectional 35 view taken on line 6—6 in Figure 5 of the toe portion of the sole, but on an enlarged scale;

Figure 7 is a transverse, sectional view taken on line 7—7 in Figure 5, but on an enlarged scale;

40 Figure 8 is a fragmentary, side elevational view of a still further modification of a shoe sole embodying the invention;

Figure 9 is a fragmentary, transverse, sectional view taken on line 9—9 in Figure 8 of the toe 45 portion of the sole, but on an enlarged scale;

Figure 10 is a fragmentary, side elevational view of a still further modification;

Figure 11 is a transverse, sectional view taken on line 11—11 in Figure 10.

50 In the drawings 11 indicates generally one type of shoe embodying the present invention wherein the upper consists of identical side portions 12—12, a continuous toe portion 13 and a top portion 14 having an integral tongue 15 at the inner end thereof. These portions are cut in

any desired form and should be provided with complementary, adjacent edges to produce a complete upper such as shown in Figure 1. The portions along the adjacent edges are preferably provided with spaced openings 16 through which 5 lacings 17 are threaded in such a manner as to securely maintain the respective portions in assembled or unitary relation. The ends of the lacings 17 may be secured in any suitable manner such as tying as indicated at 18 and the lacings 16 may be of any desired color, preferably contrasting with the color of the leather upper portions to present a pleasing appearance.

The side portions have spaced openings 19 at their upper forward ends to receive a lace 20 of 15 the usual type for securing the shoe upon the foot. While I have illustrated one type of upper it should be understood that many different designs may be substituted therefor.

A sole 21 of the usual contour is preferably 20 molded from rubber to simulate sponge and any desirable similar material may be substituted therefor. The sole 21 more clearly shown in Figure 2 has a heel portion 22, shank portion 23, ball portion 24, and toe portion 25, the latter 25 being slightly thicker to provide for additional wearing, and all being formed integral. The inner surface of the sole 21 is of course smooth throughout, and an insole 26 may, if desired, be secured thereto to provide a soft and pleasant 30 surface for the foot.

A flange 27 extends upwardly and continuously around the outer edge of the sole and is formed integral therewith. The outer surface may be slightly tapered as shown at 28 to add to the appearance of the sole and to facilitate and molding operation. The flange 27 may extend upwardly any desirable height and is provided with a plurality of blind, transverse openings 29 spaced apart longitudinally around the flange. These 40 openings 29 are more clearly shown in Figure 6 and have normally closed inner ends 30 for a purpose to be later described.

The portions 12 and 13 of the upper are provided with a plurality of transverse openings 31 45 adjacent the bottom thereof which are spaced so as to substantially register with the openings 29 in the flange 27 as more clearly shown in Figures 3 and 4. A lacing 32 is threaded through the aligned openings 31 and 29 after the lower 50 edge of the upper is positioned inside of the flange 27 to securely maintain the sole and upper in assembled relation. This lacing 32 may be of leather or other suitable material and preferably treated to strengthen and render the same wa- 55

terproof. The openings 29 and 31 are, of course, made smaller than the cross section of the lacing 32 so that the rubber material of the flange is stretched when the lacing is threaded through the openings with the result that the rubber material tends to grip the lacing and thereby provides a substantially waterproof connection.

To additionally insure that the connection is watertight, the openings 29, as before stated, are provided with closed ends 30 so that it is necessary when threading the lace therethrough to puncture this closed end with a lace threader to permit the lacing to pass through. This pierced end tends to additionally grip the lacing securely so as to prevent water from passing therethrough.

Extending around the toe portion of the sole 21 are a plurality of spaced projections 33 to reinforce the same and to increase the wearing qualities. Directly above these projections is a continuous groove 34 extending substantially concurrently therewith and in which the adjacent openings 29 are positioned so that the lacing extending around the toe will be disposed in the groove where it will be protected from injury in the event the toe is stubbed.

It is intended, of course, that the shoe heretofore described embodying the invention is to be produced for distribution and sale in knocked-down or fabricated form. This is most desirable inasmuch as the greatest expense in the manufacture of this shoe would be in the assembling and lacing. When this latter step is eliminated and is left to the user, the shoe can be manufactured and sold at a minimum of expense and at a price very appealing to the purchaser. Practically no sales resistance is met with in the sale of this shoe because of its simplicity and exceptional quality. If an upper wears out or is damaged in any manner, a new upper may be purchased, and the same in the event the sole is worn out or damaged. Furthermore, children as well as adults get enjoyment out of assembling and lacing the shoe. Many color combinations are available which is very desirable in a sport shoe. Also lacings to match the ensemble may be employed.

While a more or less conventional shoe upper is shown, it should be understood that in place thereof the usual type of straps, etc., used in sandals, bathing slippers, etc., may be substituted, but having the same connection to the sole except that in some instances it will not require as many holes 29 as are employed in Figure 1.

In Figures 5 to 11, inclusive, modified sole structures are illustrated but still embodying the present invention. In Figure 5 the sole 35 is similar to that shown in Figure 1, but eliminates the grooves above the projection 33. This sole is also adapted for sandals and the like. In Figure 8 a sole 36 of smooth appearing rubber molded in any desired form is shown and is particularly adapted for types of shoes other than sport. An offset portion 37 is provided integral with the sole and of lesser thickness to give the appearance of a thin sole. The upper is connected in each instance in the manner as heretofore described. These molded rubber soles may also be made up in many different colors.

In Figures 10 and 11, a modified sole and upper structure is shown wherein a sole 38 of molded rubber material is provided with a pair of upstanding spaced flanges 39 and 40 which may extend continuously circumferentially or be interrupted in the event the sole is used for sandals.

The adjacent surface of the flanges may be tapered to assist in removing the mold or core. The lower portion of an upper 41 is disposed between the flanges as shown and may be secured in any suitable manner such as by cementing, lacing, stitching, etc. An offset portion 42 is provided integral with the sole and of lesser thickness to give the appearance of a thin sole.

While I have described the preferred embodiment of the invention, it should be understood that I am not to be limited thereto inasmuch as changes and modifications may be resorted to without departing from the spirit of the invention as defined in the appended claims.

What is claimed is:

1. In a sole for shoes and the like, an upstanding, continuous flange secured to the marginal edge thereof, said flange being provided with a plurality of spaced openings closed at one end thereof.

2. In a sole for shoes and the like, an upstanding, continuous flange secured to the marginal edge thereof, said flange being provided with a plurality of spaced openings and a peripheral groove adjacent one end thereof in superimposed relation with respect to the adjacent openings.

3. In a molded rubber sole for shoes and the like, an upstanding flange united to the marginal edge thereof, said flange being provided with a plurality of spaced openings normally closed at one end thereof.

4. In a molded rubber sole for shoes and the like, an upstanding flange united to the marginal edge thereof, said flange being provided with a plurality of spaced openings normally closed at one end thereof and a peripheral groove adjacent one end thereof in superimposed relation with respect to the adjacent openings.

5. In a molded rubber sole for shoes and the like, an upstanding flange united to the marginal edge thereof, said flange being provided with a plurality of spaced openings, and a plurality of spaced projections at one end thereof disposed beneath said openings.

6. A shoe of the character described comprising a sole of molded rubber having an upstanding, continuous flange united to the marginal edge thereof, said flange being provided with a plurality of spaced openings closed at one end by a ruptured web, an upper portion having a plurality of spaced openings along the lower edge thereof in substantial registry with the openings in said flange, and a lacing threaded through said openings and ruptured webs to secure said upper and sole in assembled relation.

7. A shoe of the character described comprising a sole of molded rubber having an upstanding, continuous flange united to the marginal edge thereof, said flange being provided with a plurality of spaced openings and further having a peripheral groove around the toe portion in superimposed relation with respect to the adjacent openings, an upper portion having a plurality of spaced openings along the lower edge thereof in substantial registry with the openings in said flange, and a lacing adapted to be threaded through said openings to secure said upper and sole in assembled relation, a portion of said lacing being disposed in said groove.

8. A shoe of the character described comprising a sole of molded rubber having an upstanding, continuous flange united to the marginal edge thereof, said flange being provided with a

plurality of spaced openings and further having a peripheral groove around the toe portion in superimposed relation with respect to the adjacent openings, and a plurality of spaced projections united to the outer end of the toe portion beneath said groove.

9. In a sole for shoes and the like, a plurality of upstanding spaced flanges united to the marginal edge thereof, said flanges being provided

with a plurality of spaced openings normally closed at one end thereof.

10. In a sole for shoes and the like, at least one upstanding flange secured to the marginal edge thereof, said flange being provided with one or more spaced openings and a peripheral groove in superimposed relation with respect to said openings.

IRL B. CALVIN.
